United States Patent Office.

J. B. CASE, OF FLETCHER, VERMONT.

Letters Patent No. 76,050, dated March 31, 1868.

IMPROVED LEVER-PURCHASE.

The Schedule referred to in these Letters Patent and making part of the same.

TO ALL WHOM IT MAY CONCERN:

Be it known that I, J. B. CASE, of Fletcher, in the county of Franklin, and State of Vermont, have invented a new and improved Lever-Purchase; and I do hereby declare that the following is a full, clear, and exact description thereof, which will enable those skilled in the art to make and use the same, reference being had to the accompanying drawings, forming part of this specification.

This invention relates to a new and improved method of constructing a support for the fulcra of levers, and of combining the lever therewith, whereby a motion of the arms of a lever is permitted in any direction. It consists of a block, provided on the upper end with grooves or bearings to receive the trunnions of a lever-plate, said block rotating on a pivot in a stationary stand. In the accompanying plate of drawings—

Figure 1 is a plan view of my invention, the lever being removed.

Figure 2 is a central vertical sectional view of the same, with the lever upon the same, taken in line xx , fig. 3.

Figure 3 is a front view of the same.

Figure 4 is a modification of the same.

Similar letters of reference indicate corresponding parts.

A is the stand. B is the block. C is a pivot on the stand A. D is the lever-plate. a are trunnions on the same. a^1 are grooves or bearings on block B to receive the trunnions a . a^2 is an eye on the under side of the lever-plate D. The stand A is made of cast iron or wood, or other suitable material, circular in form, and of sufficient size to support the block B. Said stand A is provided with a suitable shoulder or shoulders, to receive and give suitable bearings to the block B, and has upon the upper side of the same, either a part thereof or rigidly secured thereto, a strong iron pivot projecting upwards from the centre of the stand A, as shown in the drawing, fig. 2. The pivot C may be of about the length of three inches, or of sufficient length to support the block B upon the same.

The block B is a solid cast-iron block, cylindrical in form, of about six inches in diameter, and about five inches in height, or the same may be of any convenient diameter and height, having two opposite sides slanting upwards, so as to leave a space at the top only sufficient to support the trunnions a , and terminates also at the top in a projection on each side, in which is a groove, a^1 , to receive the trunnions a , and has also a cavity in the centre of the top to receive the ear a^2 of the plate D. Said block B is chambered out on the under side, so as to form a lip, which, fitting upon a shoulder on the stand A, serves, with the aid of the pivot C, to keep the block B in position on the stand A. Said block B is also bored out on the under side, in the centre of the same, so as to receive the pivot C, and so as that the block B will be supported by and rotate easily upon the pivot C.

The lever-plate D is made also of cast iron, of any convenient length, as of the length of one foot, and of the width of about three inches, and of the thickness of about one inch, or of any other width and thickness to support any lever bolted upon the same. Upon the under side of said plate D, and rigidly secured thereto, or a part of the same, and extending across the centre, and beyond the same, on each side, are the cast-iron trunnions a , which, resting in the grooves a^1 of the block B, form a fulcrum, on which the lever-plate turns, so as that, in connection with the block B, rotating upon the pivot C, forming a universal joint, the arms of any lever upon the plate D may be made to take any desired position. Upon the under side of the plate, and in the centre thereof, is cast an eye or projection, a^3 , which serves to strengthen and steady the plate D. Any lever may be secured by bolts, or otherwise, to the plate D. The stand A may be bolted to a stone-boat or other vehicle, by means of which the whole may be moved from place to place.

The operation is readily seen from the drawing and above description. At fig. 4 is shown the block B, provided with set-screws, E E, the points of which latter enter and traverse in an annular groove, F, in the stand A, for the purpose of holding the lever fixed at any point of its horizontal motion, and also for the purpose of keeping the block B from becoming displaced from the pivot C.

Constructed as above described, it constitutes a strong and convenient lever-purchase for raising stones or other materials, the advantage of which is that the arms of the lever may be made to take any desired position.

I claim as new, and desire to secure by Letters Patent—

1. A universal joint-lever purchase or lever-support, substantially as shown and described, and for the purpose set forth.

2. The lever-plate D, in combination with the trunnions a, and block B, and pivot C, substantially as shown and described, and for the purpose set forth.

3. The block B, in combination with the stand A, and pivot C, and any lever-arm D, substantially as shown and described, and for the purposes set forth.

4. The combination of the set-screws E E with the groove F, in the stand A, and with the block B and lever D, all constructed and operating substantially as and for the purpose shown and described.

The above specification of my invention signed by me, this 23d day of December, 1867.

J. B. CASE.
